UNITED STATES PATENT OFFICE.

WESLEY H. BAUCK, OF MERCHANTVILLE, AND LOUIS R. MOTE, OF CAMDEN, NEW JERSEY.

TOWEL-RACK.

1,359,783.

Specification of Letters Patent. Patented Nov. 23, 1920.

Application filed March 30, 1920. Serial No. 370,032.

To all whom it may concern:

Be it known that we, WESLEY H. BAUCK, a citizen of the United States, residing at Merchantville, in the county of Camden and State of New Jersey, and LOUIS R. MOTE, a citizen of the United States, residing at Camden, in the county of Camden and State of New Jersey, have invented new and useful Improvements in Towel-Racks, 10 of which the following is a specification.

Our invention relates to new and useful improvements in towel racks, and has for its object to provide an exceedingly simple and effective device of this character which 15 may be readily and quickly secured to the roll flange of a bath tub in order that the towels or other articles supported by the rack will be within easy access of the user of the bath tub.

20 A further object of the invention is to provide a clamp having a towel rack of this character a portion of which will rest upon the outer face of the roll flange while the other portion projects beneath said flange 25 so that a screw carried thereby will impinge against the inner face of the flange directly beneath the imaginary line drawn through the legs of the towel rack the space within said flange being filled by a filler of wood 30 or other suitable material which will be engaged by a portion of the clamp so as to prevent swinging of the towel rack and thus preventing said towel rack from becoming accidentally disengaged from the bath tub.

35 Another object of the invention is to provide a clamp in combination with the towel rack which may be placed on the bath tub without the use of an adjusting screw the roll flange of the bath tub acting as a cam 40 for the legs of the towel rack so that when the rack is in its adjusted position it will be firmly held against accidental displacement.

With these ends in view, this invention 45 consists in the details of construction and combination of elements hereinafter set forth and then specifically designated by the claims.

In order that those skilled in the art to which this invention appertains may understand how to make and use the same, we will describe its construction in detail, referring by numerals to the accompanying

drawings forming a part of this application, in which:

Figure 1, is a side elevation of a bath tub 55 with our improved towel rack attached thereto.

Fig. 2, is an end view thereof with a portion of the tub broken away to clearly illustrate the manner of attachment of the towel 60 rack.

Fig. 3, is an enlarged side elevation of the towel rack viewed from the side of the bath tub, a portion of said bath tub being shown and illustrated in section. 65

Fig. 4, is a similar view at right angles to Fig. 3.

Fig. 5, is a perspective view of the lower end of the towel rack with a section of the bath tub illustrating a modified form of our 70 invention showing the manner in which the towel rack embodying this form is applied to the bath tub.

In carrying out our invention as here embodied, 2 represents a bath tub having a roll 75 flange 3 around its upper edge and to this roll flange is to be attached our towel rack which comprises a vertical standard 4 carrying horizontal arms 5 at or adjacent its upper end, said arms being stationary or 80 revolvably mounted on said standard while at the lower end of the standard are located the two diametrically opposite feet 6 and the ends of these feet which contact with the bath tub may be covered by suitable 85 non-scratching caps 7 of rubber or suitable material which prevent the feet from coming in direct contact with the surface of the bath tub.

Projecting from the lower end of the 90 standard 4 or from the upper ends of the feet 6 at right angles to the latter is a clamp member 8 the lower end of the upright portion 9 being spaced a sufficient distance from the feet 6 as to pass or engage the outer 95 edge of the roll flange when the feet 6 are located on the center line thereof as shown in Fig. 4, and from the upright portion 9 extends an inwardly projecting finger 10 adapted to underlie the roll flange and 100 through this finger is threaded a clamping or adjusting screw 11 located and adapted to engage the end face of the roll flange on an imaginary line passing through the cen-

ters of both feet 6 so that the clamping action of said screw will be directly in line of the standard 4 in order to support the finger 10 and prevent it moving into the 5 concaved portion of the roll flange which would permit the swinging of the towel rack so as to be dislodged we provide a 10 filler 12 of some suitable material such as wood which conforms to the shape of the underside of the roll flange and this filler is provided with a hole 13 through which the screw 11 passes.

From the foregoing description it will be seen that a towel rack threaded in the manner above described may be readily and quickly attached to a bath tub having a roll flange by backing the clamping 11 out of the finger 10 a sufficient distance to permit the passage of said finger beneath the roll 20 flange with the filler in place when the screw is adjusted as shown in Fig. 4, the legs 6 will be firmly drawn against the outer face of the roll flange so as to firmly hold the towel rack in place.

25 In Fig. 5 we have shown a slightly modified form of our invention in which the clamping screw 11 is eliminated, but otherwise the construction is identical. In this form of our invention the clamping member is sprung under the roll flange with the finger 10 and the legs 6 at an angle to the longitudinal center of the roll flange so that the outer or contacting ends of said legs engage the outer face of the roll flange with 35 one foot lying on each side of the vertical center of said flange then by turning or rotating the entire rack in that direction which will cause the contacting ends of the legs 6 to ride upon the roll flange toward its 40 vertical center, said flange will act as a cam to firmly hold the rack in its normal position when the two legs are in alinement longitudinally of the roll flange which can be accomplished because of the resiliency of the 45 clamp member constructed as here illustrated.

Of course we do not wish to be limited to

the exact details of construction as herein shown as these may be varied within the limits of the appended claims without departing from the spirit of our invention.

Having thus fully described our invention, what we claim as new and useful is:—

1. A towel rack adapted to be attached to the roll flange of a bath tub, a filler corresponding to the shape of the under surface of said roll flange, a standard, legs for supporting said standard, said legs projecting in diametrically opposite directions and adapted to overlie the vertical center of the roll flange, a clamp member projecting from said standard and adapted to pass the outer edge of the roll flange, an inwardly projecting finger forming a part of said clamp member underlying the roll flange and contacting with the filler, a screw carried by the finger and passing through the filler so as to impinge against the inner face of the roll flange on an imaginary line drawn through the centers of the legs in vertical alinement with the standard, and arms carried by the upper end of said standard.

2. In a device of the character stated adapted to be attached to a bath tub having a roll flange, of a standard, legs carried by 75 said standard for supporting the same, said legs projecting in diametrically opposite directions adapted to overlie the vertical center of said flange when in their normal positions, a clamp member projecting from the 80 standard adapted to pass the outer edge of the flange with a finger projecting beneath said flange, the outer surface of said flange acting as a cam for the legs to draw the parts firmly to their normal positions when 85 the device is attached, a wood filler underlying the flange in the region of the clamp member so as to be engaged by the finger thereof and arms supported by the standard.

In testimony whereof, we have hereunto 90 affixed our signatures.

WESLEY H. BAUCK.
LOUIS R. MOTE.
